UNITED STATES PATENT OFFICE.

ALEXANDER L. GREENABAUM, OF CHICAGO, ILLINOIS, ASSIGNOR TO O. E. JORDAN COMPANY, OF EAST CHICAGO, INDIANA, A CORPORATION OF INDIANA.

RAILROAD WAY CONSTRUCTION AND MAINTENANCE CAR.

Application filed August 7, 1922. Serial No. 580,161.

To all whom it may concern:

Be it known that I, ALEXANDER L. GREENABAUM, a citizen of the United States, and a resident of Chicago, Illinois, have invented 5 certain new and useful Improvements in Railroad Way Construction and Maintenance Cars, of which the following is a specification.

My invention relates generally to improvements in machines for constructing and maintaining railroads, but has particular reference to machines for use in ballast shaping, bank shaping, ditching and operations incident thereto.

10 In the operation of preparing or maintaining railroad road beds it is common practice to utilize a railroad car having a material spreading wing at the side thereof, and in some of the operations to provide an additional wing or member whereby material engaged by the spreader wing, and not needed for the road bed, may be shifted or moved to the end of the spreader wing and then passed on to the extension wing for disposal purposes. At times considerable bodies of earth or other material are encountered and must be shifted. In some of the operations it is necessary to shape the sloping sides or banks through cuts, the angle 15 of which must be different under varying conditions. As a result of the foregoing conditions obtaining in practice an adjustable structure is necessary and yet the strains imposed are such as require a very substantial 20 construction. At the same time railroad rights of way are of fixed dimensions at certain points, such as at tunnels, bridges and the like, so that the size and construction of the parts must be such that they can readily be positioned for passage of the car through such places.

The general object of my invention is to provide an improved car of the above character which shall have flexibility in use, and which at the same time shall be better able 25 to withstand operating conditions.

Another object of my invention is to provide a construction which can be utilized for the purpose of carrying material, such as may be met with in ballast shaping, ditching and other operations, for a considerable distance and which can be quickly and easily adjusted for use as a bank builder or shaper, and which shall have means so that when so

positioned, it shall be rigidly held against 55 undesired movement.

Another object of my invention is to provide a spreader wing and an adjustably attached bank builder wing or shaper whereby the material may be shifted from the 60 spreader wing to the bank builder or shaping wing with a minimum of resistance to such movement or passage.

Again it is an object of my invention to improve the structural characteristics of the 65 connection between the side or spreader wing and an end bank builder or shaping wing better to withstand the great strains that are imposed upon the bank builder under 70 conditions of practical use.

Another object of my invention is to provide a bank building, shaping, and material carrying wing of improved form and of such construction that it can be readily attached 75 to the spreader wings of railroad spreaders of types in current use.

My invention consists generally in a structure of the form, construction, arrangement and co-action of the various parts thereof whereby the above named objects, together 80 with others that will appear hereinafter are attainable; and my invention will be more readily understood by reference to the accompanying drawings which illustrate what I consider, at the present time, to be the preferred embodiment thereof.

In said drawings:

Fig. 1 is a plan view of a railroad car embodying my invention.

Fig. 2 is a fragmentary detail view taken 90 substantially along the line 2—2 of Fig. 1, but being upon an enlarged scale.

Fig. 3 is a top plan view of the part shown in Fig. 2.

Fig. 4 is a rear elevation of the car, certain of the duplicate parts being omitted.

Fig. 5 is a fragmentary view of the rear face of a wing construction of modified form embodying my invention; and

Fig. 6 is a top plan view of the construction shown in Fig. 5.

In the drawings I have shown my invention as combined with or as a part of the well known Jordan railroad spreader such as is disclosed in the O. F. Jordan Patent 116 No. 996,256 of June 27, 1911. This, it should be understood is by way of illustration and not by way of limitation.

The car is provided with the usual trucks 1, positioned at each end. Thereon is mounted a flat car body portion 2. At a point somewhat forward of the middle of the car there are provided vertical columns 3 which are secured to the opposite sides of the underframe of the car and which extend nearly to the rails. Mounted for vertical sliding movement in the vertical columns 3 are posts 4. The ballast shaping wing 5 is or may be operated by the same mechanism that is utilized to operate the spreader wing 12 of the standard Jordan spreader, before referred to. It is attached at one end to the movable hinge posts 4 which are freely slideable, as before stated, in the columns 3. These posts are operated by means of compressed air engines 6—6 and the car is equipped with a compressed air reservoir 7 suitably connected to the engines 6—6. It is not thought necessary to detail the pipe connections inasmuch as they are fully disclosed in the aforesaid patent and are furthermore well known in use. The two sides of the car are exactly alike except that the parts occupy reverse positions, and for this reason a description of one side and its operating mechanism will suffice for both.

It should be understood that the mechanism on each side of the car is independently operable and that either one or both thereof may be used at the same time, depending upon the work to be done. The post 4 carries a heavy hinge 8 on its lower part and to this is secured a heavy hinge section 9. The pivot pin 10 of the hinge occupies a vertical position and the wing 5 is pivoted to the part 9 by means of a horizontal pivot pin 11. The two pivot pins being at right angles allow the wing 5 to swing in both horizontal and vertical positions. The horizontal movement occurs in distending and retracting the wing to and from its working position and the vertical movement when it is desired to incline the same at any desired angle to the horizontal plane in the ballast shaping of the road bed. The free end of the wing 5 is sustained and also braced by an adjustable telescopic brace member 12, the lower end of which is pivotally attached to the wing 5 as indicated at 13. At the upper end, it is vertically pivoted at 14 to a bracket 15 upon the upper part of the post 4. The wing 5 being attached to the post, obviously rises and falls therewith. For holding the wing distended against the ballast which it must displace as the car moves forward braces are provided. These braces may be one or more in number and they may be made in a number of different ways. As here shown I have provided a plurality of braces 16 which extend from the side of the car to the inner side of the wing and which are constructed and operated as are similar braces in said Patent No. 996,256. These

members serve both as braces and as toggle levers which, when the shaft 17 is rocked by means of the air engine 18, serve to throw or move the wing 5 outwardly to operative position or inwardly to inoperative position. 70 The wing 5 may be formed in various ways and the bottom edge thereof may assume any desired configuration depending upon the shape that is to be given to the road bed. As is shown in Fig. 4 the bottom edge of the 75 wing 5 is straight whereas in the modified form shown in Fig. 5 the wing 5 is provided with a ditch-cutting portion which will be described in detail hereinafter.

To the outer end of the wing 12 I attach 80 a wing 19 which serves as a bank shaping and material carrying or shifting wing. It should be understood that the wing 5 engages the material upon what will be termed the forward side 20 and that 21 denotes the 85 rear side, across which material does not move in the displacing operation. In certain of the operations material will be engaged by the wing 5 and will move to the outer end of the wing 5 and thence on to 90 the extension or outer wing 19. I have provided a construction whereby a minimum of resistance is encountered by the material in this movement and also which imposes a minimum of strain on the outer wing 19 95 which extends quite a considerable distance from the side of the car end which therefore is not as well adapted to withstand great strains. To the rear side of the wing 5 I attach, as by means of a horizontal pivot 22 100 a hinge member 23.

The hinge member 23 is provided with spaced portions 24 and 25 to accommodate a central hinge portion 26 that is carried by the outer wing 19. A vertical hinge pin 105 27 passes through the parts 24, 25 and 26. The pivot pin 27 is at right angles to the pivot pin 22 so that the wing 19 can be caused to swing vertically and horizontally. That is to say, it may be positioned at different angles vertically with respect to the wing 5 as may be necessary to provide the proper slope to the bank or cut 28 (see Fig. 4). When positioning the wing 19 at these different angles for bank shaping purposes, it 110 should be understood that swinging movement of the parts takes place on the horizontal pivot 22. In order to lock the parts in any said position I have provided a plurality of openings 29 in the wing 5 and an opening 30 in the member 23, which opening is adapted to register with the openings 29. A pin 31 is provided for locking the part 23 when it is positioned with its opening coinciding with the desired opening 29. When the wing 19 is used for bank shaping purposes swinging movement on the vertical pivot 27 is not only not desired, but is objectionable. I have, therefore, provided means whereby the part 23 and wing 19 can in effect be made 115 120 125 130

one part for bank shaping purposes. To this end I have provided the member 23 with a projecting lug 32 and a wing 19 with an extending portion 33 having an opening 34 therein adapted, when the wing 19 is swung to the position shown in the drawings, to accommodate the lug 32. A portion of the lug 32 projects beyond the face of the extension 33 and a locking pin 35 is provided to hold the portion 33 against the hinge portion 23. Thus the wing 19 and the member 23 can be freely swung on the horizontal pivot 22 and movement on the pin 27 is positively prevented. The desired stability is thereby obtained.

As a further means of bracing the wing 19 I may provide a strut 36 which extends between the brace 12 and the wing 19. This is an adjustable brace so that the wing 19 can be braced in its different placed positions. For bracing the wing 19 away from the car I have here shown a plurality of braces 37 which are similar to the braces 16 and which are actuated by the rocking of the shaft 17, as before explained. While two braces 37 are shown, this number may be more or less, depending upon the size and construction of the wing 19, and the size, shape and construction of the brace. It should be obvious that when the shaft 17 is rocked, both the wing 5 and the wing 19 will be simultaneously moved to a position parallel the car as is indicated in full lines upon the other side of the car in Fig. 1.

The wing 19 is adapted to function for another purpose. That is to say for the purpose of carrying material which is collected in ballast shaping, ditching or otherwise for a considerable distance along the right of way. This mechanism is intended to carry the material along with the car through deep cuts and then to waste the same over the bank at the end of the cut, or in the event the cut is a long one to gather the same into spaced piles in the cut for convenient removal later on. When it is to be used for this purpose the wing 19 is swung to the dotted line position shown in Fig. 1 and its outer end is connected by means of a rigid brace 38 to the forward end of the car. Before it can be swung to this position, however, the locking pin 35 must be removed and it can then be swung freely upon the vertical pivot 27. It should also be understood that when the wing 19 occupies the dotted line position shown in Fig. 1 it will usually occupy a horizontal position. It should also be understood that the brace or braces 37 are removed and that when the brace or braces 16, or the other means that control the movement of the wing 5 are actuated to swing the wing 5 inwardly, the wing 19 will occupy a position on the outer side of the wing 5 and substantially parallel to it as is indicated by means of dotted lines

on the far side of the car in Fig. 1. Likewise when the wing 5 is swung outwardly the wing 19 will automatically be swung to proper operative position.

In Figs. 5 and 6 I have illustrated a modified structure embodying my invention but inasmuch as the main wing and the outer wing correspond generally to the main and outer wings of the form first described they have been given similar reference characters. The modified structure applies to the means for joining the wings 5 and 19. As here shown the wing 5 has rigidly secured thereto as by means of rivets a hinge member 39 having spaced hinge lug portions 40. The outer wing 19, in turn, is secured to a hinge member 41 as by means of a horizontal pivot 42. The member 41, in turn, is provided with a hinge lug extension portion 43 that is accommodated between the spaced lugs 40. A vertical hinge pin 44 secures the parts 41 and 39 together in such manner as to permit swinging movement thereof. The wing 19 may obviously swing on the horizontal pivot 42 so that it may occupy different angular positions as may be necessary to properly shape the bank 28. In order that the wing 19 may be locked in its placed angular positions the member 41 is provided with a plurality of holes 45 and the wing 19 with a hole adapted to register therewith. A locking pin 46 is provided, adapted to pass through the aligned holes in the member 41 and wing 19.

As here shown the wing 5 is provided with a ditching extension 47. It should be obvious that the wing 19 as constructed and attached in Figs. 5 and 6 is likewise adapted to be swung to the various positions referred to with respect to the construction shown in Figs. 1 to 4, inclusive, and also that the material in passing from the wing 5 to the wing 19 encounters a minimum of resistance because of the mounting of the hinge and connecting parts rearwardly of the face 20 of the wing 5.

The many advantageous characteristics of my invention will now be understood by those skilled in this art without further comment.

For convenience in the claims, the wing having the functions of the wing 5 will be termed a side wing and the wing having the functions of the wing 19 an outer wing.

I claim:

1. The improvements herein described comprising a car in combination with a side wing, an outer wing and means joining the outer and side wings, said means including a hinge structure secured to the rear side of the side wing, said outer wing being thereby disposed rearwardly of the forward face of the side wing, vertically and horizontally disposed pivots, and coat-

ing means on said wings for locking the outer wing in a fixed position with respect to the side wing.

2. The improvements herein described comprising a car in combination with a side wing, an outer wing, a vertical pivot joining the outer and side wings, and coacting means on said wings including an interfitting lug and slot for locking the outer wing against swinging movement on the vertical pivot.

3. The improvements herein described comprising a car in combination with a side wing, an outer wing, a hinge plate operatively connected to the rear side of said side wing at its outer end, means on the inner end of said outer wing connected to said hinge plate so that said outer wing may swing about a vertical axis arranged back of the plane of the front face of said side wing, and coacting means carried by said hinge plate and said end of the outer wing for securing said outer wing against movement about said vertical axis.

4. The improvements herein described comprising a car in combination with a side wing, an outer wing, a hinge plate operatively connected to the rear side of said side wing at its outer end, means on the inner end of said outer wing connected to said hinge plate so that said outer wing may swing about a vertical axis arranged back of the plane of the front face of said side wing, said hinge plate and said end of the outer wing having interengaging parts and means parallel with said vertical axis and so arranged with respect to said interengaging parts as to lock said wings

against relative movement about said vertical axis.

5. The improvements herein described comprising a car in combination with a side wing, an outer wing, a hinge plate operatively connected to the rear side of said side wing at its outer end, means on the inner end of said outer wing connected to said hinge plate so that said outer wing may swing about a vertical axis arranged back of the plane of the front face of said side wing, a lug on said hinge plate adapted to extend through a slot in the inner end part of said outer wing, and a pin passing through said lug to hold said outer wing against movement about said vertical axis.

6. The improvements herein described comprising in combination with a side wing, an outer wing, a plate operatively secured to the rear face of said side wing at its outer end and having a rearward extension thereon, said plate being capable of a pivotal movement about a horizontal axis, means on the inner end of said outer wing adapted to be pivotally connected to said hinge plate by means of an axis arranged at a right angle to said horizontal axis, there being an extension on the inner end of said outer wing, which extension has a slot therein to receive said rearward extension when said wings are in their extended position, and means associated with that part of said rearward extension beyond said slot to lock said wings in their extended position.

In testimony whereof, I have hereunto set my hand, this 31st day of July, 1922.

ALEXANDER L. GREENABAUM.
